UNITED STATES PATENT OFFICE

103,955

DESIGN FOR A SHADE PULL

Edith Richcreek, St. Petersburg, Fla.

Application September 28, 1936, Serial No. 65,034

Term of patent 3½ years

To all whom it may concern:

Be it known that I, Edith Richcreek, a citizen of the United States, residing at St. Petersburg, in the county of Pinellas and State of Florida, have invented a new, original, and ornamental Design for a Shade Pull, of which the following is a specification, reference being had to the accompanying drawing, forming part thereof.

I claim:

The ornamental design for a shade pull, as shown.

EDITH RICHCREEK.
